(57) CLAIM

The ornamental design for a jet massager with moveable jet, as shown and described.

DESCRIPTION

FIG. 1 is a front elevational view of one embodiment of a jet massager with moveable jet in accordance with my invention;

FIG. 2 is a front elevational view with the moveable jet in another position thereof;

FIG. 3 is a front elevational view with the moveable jet in another position thereof;

FIG. 4 is a back elevational view thereof;

FIG. 5 is a top elevational view thereof;

FIG. 6 is a bottom elevational view thereof;

FIG. 7 is a bottom elevational view with the moveable jet in another position thereof;

FIG. 8 is a bottom elevational view with the moveable jet in another position thereof;

FIG. 9 is a left side elevational view thereof;

FIG. 10 is a right side elevational view thereof; and,

FIG. 11 is a perspective view of a jet massager with movable jet.
